CARTON FOR RUBBER HEELS AND THE LIKE

Albert A. Esterson, Baltimore, Md., assignor to
Cat's Paw Rubber Company, Inc., Baltimore,
Md., a corporation of Maryland

Application April 5, 1934, Serial No. 719,213

3 Claims. (Cl. 206—46)

This invention relates to special receptacles and particularly to containers having a removable portion serving as a check for subsequent identification.

5 One of the objects of the present invention is to provide a carton for containing rubber heels, soles and the like and having a panel portion which may be removed to provide two checks, one adapted to be retained by the dealer and the other to be retained by the customer for subsequent identification of footwear having applied thereto the heels or soles originally contained in the improved carton constituting the invention.

15 Another object of the invention is to provide a carton of the character described which is adapted to temporarily hold the soles or heels in position after the panel has been removed.

With such objects in view, as well as other advantages which may be incident to the use of the improvements, the invention consists in the parts and combinations thereof hereinafter set forth and claimed, with the understanding that the several necessary elements constituting the same 25 may be varied in proportions and arrangement without departing from the nature and scope of the invention.

In order to make the invention more clearly understood there are shown in the accompanying drawing means for carrying the same into practical effect, without limiting the improvements, in their useful application, to the particular construction which, for the purpose of explanation, has been made the subject of illustration.

35 In the said drawing:—

Figure 1 is a perspective view of a cardboard or like carton constructed in accordance with the present invention, the wall preferably constituting the bottom of the carton being up-

40 permost.

Figure 2 is a plan view of the blank from which the carton is constructed, and

45 Figure 3 is a view of the removable panel portion in the bottom wall removed and separated from the carton to provide identification checks for the dealer and customer respectively.

Referring to the drawing, a carton constructed in accordance with the present invention, is shown as comprising a body 1 having top and bottom walls 2 and 3 respectively, side walls 4 and end walls 5. The carton is preferably constructed from a blank 6 shown in Figure 2, the side edges of which are provided with bendable flaps or tabs 7 adapted to be glued together to 55 form one of the side walls 4, and with end flaps

8 which are adapted to be folded over one another and united to provide the end walls 5 of the carton.

The bottom wall 3 of the carton is provided with a removable panel portion 9 which is defined by score lines 10 and which is divided transversely by a score line 11 to provide two check portions 12 and 13. Each of these check portions bears an area for corresponding identification numbers indicated at 14 and other appropriate information such as the date on which the goods marketed in the carton may be called for.

When a customer purchases a pair of rubber heels, for example, contained in a carton constructed in accordance with this invention, the dealer removes the panel portion 9 by tearing it from the carton along the weakened lines 10 and then separates the panel into two checks by tearing the same along the weakened line 11.

15 The nature of the work to be done and the day when the same may be called for is indicated in the appropriate spaces provided for the purpose on both separated portions of the panels, as will be apparent from the drawing. 25 One of the marked check portions 13 is handed to the customer while the dealer retains the remaining portion 12 together and in conjunction with the heels and footwear to which the heels are to be applied for subsequent identification.

30 The removal of the panel portion from the carton provides two longitudinally extending overhanging flanges 15 which serve to prevent the displacement of the rubber heels from the carton until the dealer is ready to apply them to the footwear. The removal of the panel portion from the carton also provides a window through which the rubber heels are or may be displayed until they are applied to the footwear.

35 If desired the dealer's portion 12 of the removable panel may be perforated as indicated at 16 so as to provide means for convenient filing and storage of the check until the goods are called for, and thereafter.

40 As best seen in Fig. 2 the top wall 2 of the carton is adapted for the reception of the trademark, description or advertising matter or other desired indicia identifying the nature and origin of the contents of the carton or package.

45 The invention is particularly useful when the carton is employed for rubber heels and obviates the expense as heretofore of printing separate repair tags to accompany the cartons containing the heels. Ordinarily, when shoes are left with a repairer to have rubber heels applied,

50

55

separate repair tags must be provided and are retained by the customer and dealer respectively for subsequent identification purposes when the goods are called for. These separate repair tags cost in the neighborhood of \$1.50 to \$2.00 per thousand to be printed, depending upon the quality, and are sometimes in excess of this amount.

According to the present invention not only are the separate repair tags or identification checks dispensed with together with the attendant expense of printing and preparing the same, but there is no possibility of the repair tags becoming separated from the merchandise or misplaced until the check is actually handed to the customer. No part of the valuable advertising is lost since the top portion of the cover has not been departed from and space is provided on the removable panel portion to include sufficient advertising matter to identify the contents and origin of the goods contained within the carton when viewed from its underside. In this manner the advertising value of the carton is preserved without added expense over cartons previously used, and the very material expense of printing separate repair tags to accompany the cartons is entirely obviated. The saving in expense of printing the separate repair tags as heretofore inures directly to the benefit of the shoe repairer with resultant advantage.

What is claimed is:

1. A job-identifying repair package containing a shoe repair element or elements, said element or elements being housed and retained within and by the walls of the package, one of said walls having a portion thereof circumscribed or partially circumscribed by a means indicating and setting off said portion as a detachable job identifying check, the configuration and location of the indicating means being such that the removal of the check does not destroy the capability of the aforesaid package to retain its contents, said detachable check bearing corresponding indicia of an identifying character and being separable between the said sections may be retained by the dealer together with the repair elements confined within the remaining portion of the package, and

the other of said sections may be retained by the customer for subsequent presentation and identification of the job.

2. A job identifying repair package containing a shoe repair element or elements, said element or elements being housed and retained within and by the walls of the package, one of said walls having a portion thereof circumscribed or partially circumscribed by a weakened line indicating and setting off said portion as a detachable job identifying check, the configuration and location of the weakened line being such that the removal of the check does not destroy the capability of the aforesaid package to retain its contents, said detachable check bearing corresponding indicia of an identifying character and being separable between the said sections into two sections, whereby one of said sections may be retained by the dealer together with the repair elements confined within the remaining portion of the package, and the other of said sections may be retained by the customer for subsequent presentation and identification of the job.

3. A job identifying repair package constructed of yieldable material containing rubber heels or the like, said rubber heels being housed and retained within and by the walls of the package, one of said walls having a portion thereof circumscribed or partially circumscribed by a means indicating and setting off said portion as a detachable job identifying check, the configuration and location of the indicating means being such that the removal of the check leaves flanges overlying said heels and capable of yieldably retaining said rubber heels within said package, said detachable check bearing corresponding indicia of an identifying character and being separable between the said sections, whereby the removal of said check provides an opening in said package through which the rubber heels may be removed by the dealer by flexing or tearing said yieldable flanges, and whereby one of said sections may be retained by the dealer together with the repair elements confined within the remaining portion of the package, and the other of said sections may be retained by the customer for subsequent presentation and identification of the job.
